UNITED STATES PATENT OFFICE.

WILLIAM F. JENNINGS, OF BRIDGEWATER, MASSACHUSETTS.

MOLDER'S TOOL.

1,198,133.

Specification of Letters Patent. Patented Sept. 12, 1916.

Application filed April 27, 1916. Serial No. 93,915.

To all whom it may concern:

Be it known that I, WILLIAM F. JENNINGS, a citizen of the United States, residing at Bridgewater, in the county of 5 Plymouth and State of Massachusetts, have invented new and useful Improvements in Molders' Tools, of which the following is a specification.

This invention relates to tools used in 10 foundry work to repair imperfections in sand molds, and particularly to add mold material to replace portions broken away from corners of the molds.

The invention is embodied in a tool or 15 slicker adapted to bear simultaneously on two faces of a sand mold, and to carry a small body or mass of the mold material to a corner break in the continuity of the mold, and restore the continuity of the corner by 20 a single movement or operation.

Of the accompanying drawings forming 25 a part of this specification, Figures 1 and 2 are perspective views of one embodiment of my invention. Fig. 3 is a section indicated by line 7—7 of Fig. 2. Fig. 4 is a section indicated by line 8—8 of Fig. 2. Figs. 5 and 6 are perspective views of a second embodiment of my invention. Fig. 7 is a section indicated by line 11—11 of Fig. 6. Fig. 8 is a section indicated by line 12—12 30 of Fig. 6. Figs. 9 and 10 are perspective views of a third embodiment of my invention. Fig. 11 is a section indicated by line 15—15 of Fig. 10. Fig. 12 is a section indicated by line 16—16 of Fig. 10.

The same reference characters indicate the same parts in all the figures.

According to the embodiment shown in Figs. 1 and 2, the tool comprises a handle 40 28 and an angular blade having a portion 25^a the operating surface of which is convex throughout its length, and a coöperative portion 26 the operating surface of which is substantially flat. This tool is particularly well adapted for mending a break at the junction of a concave portion of a mold with a substantially flat portion at approximately right angles thereto, the concave surface of the mold being slicked by the 45 convex face of the blade and the flat surface of the mold being meanwhile guarded

against distortion during the process; or the plane surface may be slicked by the flat blade portion and the concave surface be preserved by the convex blade portion. 55 When the edge of the mold is badly broken away, a small mass of mold material may be caused to adhere to the blade at the junction of the under surface of portion 25^a and the adjoining surface of the portion 26, 60 and such material may be wiped into position to form an integral part of the mold, the concave and flat surfaces being slicked simultaneously.

It will be apparent that the embodiment 65 shown in Figs. 1 and 2 is primarily for slicking molds wherein the concave portion is nearer the point of access. It will also be apparent that the form shown by Figs. 5 and 6 (which is provided with a flat blade 70 portion 25 and a convex blade portion 26^a) is adapted for repairing or slicking a mold at the junction of a flat surface and a concave surface when the flat surface is nearer the point of access than is the concave surface. 75

The embodiment shown by Figs. 9 and 10 is chiefly distinguished from the form shown by Figs. 5 and 6 by the position of the handle. The position of the handle 80 may in some cases be determined by the preference of the workman, but in other cases its location is determined by the requirements of certain classes of work.

The form shown by Figs. 9 and 10 would 85 be more advantageous than that shown in Figs. 5 and 6 if the workman were repairing, for instance, a mold arranged for casting a cylindrical object having an annular flange midway its length, the more remote mold 90 shoulder defining the junction of the cylinder and flange being the part requiring slicking or repairing.

I claim:

1. A molder's tool comprising an angular 95 blade having two divergent coöperative portions one of which has a longitudinally convex slicking face, the bulge of said convex face being in the general direction of the free end of the coöperative blade-portion, 100 and a handle for the blade.
2. A molder's tool comprising an angular

blade having two divergent coöperative portions one of which has a longitudinally convex operating face and the other of which has a substantially flat operating face, the 5 bulge of said convex face being in the general direction of the free end of the blade-

portion having the flat operating face, and a handle for the blade.

In testimony whereof I have affixed my signature.

WILLIAM F. JENNINGS.
